UNITED STATES PATENT OFFICE.

JOHN A. KENNEDY, OF TOPEKA, KANSAS.

LATCH MECHANISM FOR CLOSURES.

Application filed August 11, 1923. Serial No. 656,823.

To all whom it may concern:

Be it known that JOHN A. KENNEDY, a citizen of the United States, residing at Topeka, in the county of Shawnee and State 5 of Kansas, has invented new and useful Improvements in Latch Mechanism for Closures, of which the following is a specification.

The purpose of the invention is to provide a latch mechanism for a closure consisting of a plurality of doors or elements, and to so arrange the latch mechanism that it may be carried by one of the elements when the same are opened and yet extended 15 to latch the whole series.

The invention comprises further features and combinations of parts to be hereinafter set forth, shown in the drawings and claimed.

20 In the drawings:

Figure 1 is a view in elevation showing the outer faces of both doors and the jamb, showing the improved latch mechanism carried thereby.

25 Figure 2 is a view in elevation showing the inner faces of the doors and the jamb with the mechanism applied.

Figure 3 is a sectional view on line 3—3 of Figure 2.

30 Referring to the drawings, 1 designates the frame, 2 the door openings and 3 and 4 the doors for closing the openings. The doors are hinged to the jambs, as shown at 5.

35 Mounted in guide straps 6 on the door 3 is a slide bar 7, one end of which is pivoted at 8 to an oscillatory member 9 which is pivoted at 10 to the door. The oscillatory member 9 is, in turn, pivoted at 11 to a latch 12, one end of which engages a socket 13 in the jamb of the frame. The latch member 12 acts to keep the door 3 latched 40 at the hinged edge of the door.

45 A second latch member 14 has a bifurcated end pivoted at 15 to the other end of the sliding member or bar 7. The latch member 14, in turn, engages a socket 16 in the jamb of the other door opening for the purpose of latching the door 4 at the hinged edge thereof. In fact, since the latch member 14 is pivoted to the sliding member or bar 7 and overlies the intermediate jamb 17, the door 4 is held in closed position when the end of the latch member 14 engages with the socket 16.

55 When the latch member 14 is in a horizontal position, it engages the keepers 18, 19

and 20. These keepers are in the form of brackets which are secured to the door 4. The brackets are angular and their larger upright portions are spaced from the inner 60 face of the door so that the latch member 14, when in a horizontal position, may engage between the upright portions and the face of the door, thereby preventing the door from being opened in one direction. 65 A beading 21 is formed with the jamb of the two door openings and is engaged by both doors for the purpose of preventing movement of the door in the opposite direction.

70 It will be noted that when the latch member 14 is moved on its pivot 15 to a position to engage the strap or bracket 22, as shown in dotted lines in Figure 2, the door 4 is free to be opened. When the latch member 14 is in such position, the sliding member or 75 bar 7 may be moved to withdraw the latch member 12 from engagement with the socket 13. The latch member 12 is also mounted slidably in the angular strap guide 23 for the purpose of supporting the same in a 80 horizontal position whereby it can be reciprocated in either direction.

A spring 24 is fastened at 25 to the door 3 and is engaged with a pin 26 to tension and retain the spring in position so that the free 85 end portion of the spring will bear against the upper end of the latch member 9, holding the sliding member or bar 7 in such position as to retain the end of the latch member 14 in engagement with its socket 16. 90 When the latch member 14 is moved to the dotted line position, the sliding member or bar 7 may be reciprocated against the action of the spring 24 in order to withdraw the latch member 12 from engagement with its socket. 95 However, the sliding member or bar 7 may remain in the position shown in Figure 2 in full lines with the latch member 12 engaged with its socket, the spring 24 acting to retain the parts in such position while the door 3 may be swung open with the latch members carried thereby, allowing the other door to be opened.

The door 4, however, may be retained in its latched closed position by means of an auxiliary latch mechanism. This auxiliary latch mechanism may be operated from the exterior or through the medium of an element may be actuated from the interior. This auxiliary mechanism is provided for 100 the purpose of retaining one door in a closed latched position while the other door or clo-

sure may be opened. This auxiliary latch mechanism comprises an oscillatory member 27 which is pivoted to the door 4, as at 28, and has its opposite ends provided with slots 29. Mounted in guide straps 30 and 31 are sliding latches 32 and 33. Certain of the ends of the sliding latches 32 and 33 are connected to the oscillatory member 27 by means of the pivot connecting pins 34 and 35 which pass through the slots 29. By means of this connection, the ends of the oscillatory member 27 are permitted to move relatively to the sliding latches 32 and 33. The remote ends of the two latches 32 and 33 engage sockets 36 and 37 in the opposite jambs of the door opening 2 on the left in Figure 1. The socket 37 is formed in the jamb where the door 4 is pivoted while the socket 37 is formed in the jamb where the free edge of the door engages. A suitable spring 38 is fixed at 39 to the door 4 and engages with a pin 40. The spring is so disposed as to bear upon the oscillatory member 27 to retain the sliding latches 32 and 33 in engagement with their sockets.

The door 4 has an opening 41 adjacent where the sliding latch 32 is disposed. On the inner face of the door 4 and adjacent the upper and lower edges of the opening 41 are bearing brackets 42 for the reception of the pivot pin 43 upon which a latch actuator 44 is pivotally mounted. This latch actuator has a reduced extremity 45 which passes through the opening 41 and engages with an opening 46 in the sliding latch 32. The opening 46 is so constructed as to permit the reduced extremity to engage therewith and cause a reciprocating movement to be imparted to the sliding latch 32. The actuator 44 is substantially U-shaped and the greater portion thereof beyond the pivot pin overlies the inner face of the door 4, as shown in Figures 2 and 3.

The construction and arrangement of the actuator with relation to the sliding latches 32 and 33 are such that when the actuator is swung outwardly, the reduced extremity of the actuator will cooperate with the opening 46 in order to slide the latch 32 in the direction of the arrow *a* in Figure 3 and since this sliding latch is connected to the sliding latch 33 through the medium of the oscillatory member 27, the extremities of both latches will disengage from the sockets 36 and 37, leaving the door 3 free to be opened. However, the door 4 cannot be opened until the sliding latches are disengaged from their sockets 36 and 37. In this way, the door 4 may be retained closed while the door 3 may be opened and when the door 3 is opened, the latch mechanism, which includes the sliding member or bar 7 and the latch member 14, may move therewith while

the latch member 14 is in a tilted position. Obviously, the actuator 44 may be locked by any suitable means, such as a padlock or the like (not shown), on the interior of the door 4. When the actuator is released, provided it is locked, and tilted, it will move the sliding latch 32 in the direction of the arrow *a*, thereby tilting the oscillatory member 27 and withdrawing the remote ends of both latches from their sockets, leaving the door 4 free to be opened.

The invention having been set forth, what is claimed is:

1. A latching mechanism including a door frame with a door opening, a pair of doors hinged to the frame, a sliding bar mounted in guides on one door, a sliding latch for the door carrying the bar and operatively connected to the bar, a second sliding latch pivoted to the other end of the sliding bar and bridging said intermediate jamb and having its end operatively engaging with the jamb for latching the other door, said second sliding latch being movable on its pivot to assume an inclined position with relation to the sliding bar whereby, when the door is opened, the entire mechanism is carried therewith.

2. In a latch mechanism, a door frame having door openings, a pair of doors hinged to the jambs of said door openings, a slide bar mounted in guides in one door, a slide latch mounted in a guide of the door carrying the bar and adapted for engagement with the jamb to retain one of the doors latched, an oscillatory spring tensioned member connecting said slide latch and the slide bar, the other door having supports, a second slide latch pivotally connected to the slide bar and adapted to assume a horizontal position in engagement with the supports and with a socket in the jamb of the door opening, said second slide latch being adapted to assume a tilted position to permit the door carrying the bar to be opened.

3. The combination with a plurality of adjacent closures, of a latch mechanism mounted on one of said closures and embodying a latch for engagement with the jamb of the mechanism carried closure, a slide bar mounted on said closure and operatively connected with said latch, and a second latch member foldably connected with the slide bar and adapted for arrangement in spanning relation with the remaining closure and in engagement with the jamb thereof, said second latch member being adapted for arrangement on the mechanism carried closure when the latter is opened.

In testimony whereof he affixes his signature.

JOHN A. KENNEDY.
